UNITED STATES PATENT OFFICE.

ALBERT EDWARD CLEGG, OF LEEDS, ENGLAND.

GLASS-BOTTLE-BLOWING MACHINE.

1,133,708.

Specification of Letters Patent. Patented Mar. 30, 1915.

Application filed January 20, 1913. Serial No. 743,061.

To all whom it may concern:

Be it known that I, ALBERT EDWARD CLEGG, a subject of the King of Great Britain and Ireland, residing at Leeds, in the 5 county of York, England, have invented certain new and useful Improvements in Glass-Bottle-Blowing Machines, of which the following is a specification.

This invention relates to machines of the 10 "turnover" type for blowing and molding glass bottles by means of compressed air. Machines of this type are provided with a forked head, rotatable about a vertical axis; and with turnover frames mounted on the 15 vertical sides of the forked head and rotatable about a common horizontal axis; the connections and gearing being such, that when the head is turned around by half a revolution to bring the one of the turnover 20 frames from the front to back of the machine, and the other turnover frame from the back to the front, both turnover frames are at the same time rotated through a half revolution. Each turnover frame carries a 25 pair of swinging arms which carry at their ends the halves of the "parison" mold. Several of such machines are usually arranged around or partially around the furnace containing the molten "metal" or glass, 30 which is poured by "servers" standing at the back of the machine into the "parison" mold. "Parison" is the technical term for the hot glass in the parison mold and before being blown in the finishing mold. The 35 blower or attendant stands in front of the machine.

Now this invention consists in a new arrangement or combination of such machines in pairs, so that the rear sides of the two 40 machines are so close together, that one server can attend to two machines, while each machine has its own blower at the front attending to the blowing operations. In order to be able to place the machines of 45 each pair as close together as possible it is necessary that the forked heads of the two machines should not be rotated simultaneously, otherwise the turnover frames or the swinging arms would come in contact. This 50 invention makes provision for preventing such simultaneous rotation being started by the two attendants.

The invention is illustrated by the accompanying drawings.

55 Figure 1 is a plan, and Fig. 2 is an elevation, the left hand side being in vertical lon-

gitudinal central section of Fig. 1; the motor and gear box being omitted. Fig. 3 repeats the sectional part of Fig. 1 on a larger scale, the spindle *t* being shown in its raised 60 position and Fig. 4 is an enlarged view of the recessed collar or cam.

b' and *b*² are the pillars or pedestals of the two machines respectively, which carry the turn over heads and blowing mechanism, 65 not shown. The pedestals as shown are carried by bed plates *a*' and *a*², connected at the rear by a cross plate *d*, and at the front by a bent or curved cross plate *c* (or *c*'). Instead of being separate, the bed plates and 70 cross pieces may all be cast in one piece. The center vertical planes of the two machines, see *x* *x* and *y* *y* Fig. 1, are according to this invention inclined toward one another, the inclosed angle being conveniently 75 60 degrees or thereabout.

f is the first driving shaft, driven by an electric or other motor *e*', the axis of the shaft *f* bisecting the angle inclosed by the 80 lines *x* *x* and *y* *y*. By means of a worm on the shaft *f* and a worm wheel on the shaft *i*, inclosed by the gear box *h*, motion is transferred through the spur wheels *j*' and *j*² respectively to the wheels *k*' and *k*², mounted loose on the proximate ends of two similar 85 aligned horizontal shafts, one of which, marked *l*', is shown on Fig. 2, the other being hidden by the parts which surround it; the shafts being rotated at the proper times from the wheels *k*' and *k*² by means of friction driving cones, *n*'. The ends of the said 90 two shafts drive by means of 2 to 1 bevel gears 7 the vertical driving shafts 6 of the blowing machines.

8 is a stop rod, normally held in the raised 95 position by a spring, not shown, in which position it locks the turnover head against rotation, and indirectly against the driving shaft such locking being effected by the entrance of tip of rod 8 into notch 12 of a bevel gear-wheel disk *C*^a, which turns with the head *d*', being practically a part thereof. Said disk is the last of a train of bevel gears *C*', *C*² and *C*³, whereby the head is driven 100 from shaft 6. The stop rod 8 is drawn down to release the turnover head by pressing on the foot lever 9. The construction of each head and appurtenances is substantially the same, including the driving and locking devices. The clutch *n*' is fitted on the shaft 105 *l*', (or the corresponding shaft) with a sliding key or keyway, so that it can be 110

pressed against the internally coned rim of the wheel k' (or k^2) by the spiral spring g , which bears at its other end against the collar r fixed on the shaft l .

- 5 The spiral spring is surrounded by the muff or sleeve o , which is secured to the boss of the clutch cone n' or formed integral therewith. The outer end of the sleeve o has a collar formed on it; and a recess s , 10 see Figs. 2 and 4, is made on the inner side of the collar, forming it into a cam. A vertically guided spindle t , normally pressed upward by the spring u , is so situated with respect to the collar of the sleeve o , that 15 when the cone clutch n' is pressing against k' , see the left side of Fig. 2, the upper end of the spindle t springs upward into the recess s , when the rotary movement brings the recess opposite the upper end of the spindle t . 20 The continuation of the rotary movement causes the upper end of the spindle t to force back the sleeve o , see the right side of Fig. 2, and with it the clutch cone n' , thus 25 stopping the rotation of the shaft l' , therefore fore of the driving shaft 6 also.

The spindle t is drawn down by the depression of the foot lever w , through the connections, shaft 1, lever 2, link 3, bell crank lever 4, and stud pin t' engaging in a 30 slot in one of the arms of the bell crank lever 4. A hinged two armed lever 10 is carried so that its ends are always in contact with the bottom of the two spindles, and thus while not preventing the upward 35 movement of either of the spindles, prevents the simultaneous downward movement of the two spindles, and hence, the friction clutches connecting the said two alined shafts with the motor shaft f from coming 40 into engagement simultaneously; so that the shafts 6 and, consequently the turnover heads of the two machines cannot be rotated simultaneously *i. e.* independently. This allows the two machines to be placed 45 closer together than could be done if there were any risk of the turnover heads or the mechanism carried by them coming in contact, thus permitting a larger number of machines being arranged around one furnace and dispensing with half the servers. 50

The connected operation of the parts described is as follows: The attendant or blower at one of the machines depresses the foot lever w of his machine, drawing down 55 the corresponding vertical spindle t and allowing the clutch mechanism to connect his machine with the driving shaft f of the motor, and through the lever 10 to raise the vertical spindle t of the other machine so as 60 to disconnect the driving shaft of such machine from the motor shaft f . The last portion of the downward movement of the lever w depresses the lever 9, drawing down the stop rod 8, so as to unlock the turnover 65 head of this machine. When the corre-

sponding shaft of the two said alined shafts completes one revolution, the turn over head making half a revolution, the upper end of the corresponding spindle t springs up into the recess s , and thus arranges the parts for action which brings the machine to a standstill, the foot lever w being brought to its original position. As the spindles t merely rest on the ends of the lever 10, the other machine is not started until the other blower or attendant depresses his foot lever w . The starting of each machine is thus absolutely under the control of its attendant.

Having now described my invention what I claim is:—

1. In glass bottle blowing machines having turnover heads the combination of two machines placed side by side and at an angle to one another having their backs closer together than their fronts, with a motor having its driving shaft midway between the two machines, two independent shafts at right angles to the motor shaft, a loose clutch wheel on each of the independent shafts, gearing from the motor shaft to both of said clutch wheels, coöperatiye clutch members having sliding keyway and key connections to said independent shafts, two-to-one bevel gears from the ends of said independent shafts to the driving shafts of the machines respectively, a spring around each of said independent shafts between a collar fixed to the shaft and the corresponding clutch member, a recessed cam collar secured to said clutch member, a vertically guided and upwardly spring pressed spindle below each cam collar, lever link and shaft connections from the bottom of each spindle to a corresponding foot lever and a two armed lever having its ends in contact with the bottoms of said vertical spindles substantially as shown for the purposes specified.

2. The combination of two turnover glass bottle blowing machines having their adjoining sides inclosing an angle of 60 degrees or thereabout, with an electric motor placed with its shaft bisecting said angle, worm and worm wheel gear from the motor shaft to a counter shaft, two independent horizontal shafts, spur gears from the ends of the counter shaft respectively to friction clutches on said independent shafts and gear wheels from the independent shafts to the first motion shafts of said machines respectively, substantially as described.

3. In a pair of glass turnover machines placed side by side the combination of a friction clutch driven shaft, a collar fixed on each shaft of each machine, a spring situated between said fixed collar and the slideable member of the friction clutch, a cam connected to said slideable member, a cam-contact spindle, a spring acting on said clutch to move it into operative position and

intervening mechanism which is arranged and adapted to prevent the simultaneous action of the two clutches.

4. In a pair of glass bottle blowing machines of the turnover type placed side by side and having separate clutch and motor shafts and starting mechanism for each of said machines, the combination of two cam-contact spindles and two cams operating as 10 described on the slideable members of the friction clutches, means for preventing the simultaneous actuation of the machine heads from said starting mechanism and means connecting said preventing means to 15 said cam spindles for the purpose set forth.

5. In a pair of glass bottle blowing machines of the turnover type, stop devices for the turnover heads, a pair of levers in said machines respectively, for actuating said 20 devices, starting mechanism for each of said machines, an additional pair of levers for said starting mechanism, each of which is arranged above a lever of the first pair in order that its continued depression may 25 actuate the same and means for preventing the simultaneous actuation of the heads from said starting mechanism.

6. In combination with a pair of juxtaposed turnover glass bottle blowing machines, arranged with their turnover heads 30 too near each other for simultaneous rotation, locking devices for said heads respectively, a pair of levers, one of which is attached to each of said machines and connections between said levers and said locking devices whereby the same movement of either of said levers will free one machine 35 only, while leaving the other locked to guard against simultaneous rotation of both 40 machine heads.

7. A pair of juxtaposed turnover glass bottle blowing machines provided with turnover heads which are arranged too near each other for simultaneous rotation, in combination with means for rotating said 45 turnover heads, starting mechanism, for each head and devices for preventing the starting mechanism of both heads from operating simultaneously.

8. In glass-bottle blowing mechanism, a 50 pair of rotary mold-carrying turnover heads which are arranged too near each other for simultaneous rotation, a pair of clutches governing the individual rotation of the said heads, a pair of cams slideable with said 55 clutches, a pair of vertically movable parts arranged for contact with said cams when said parts are in their highest position, a lever arranged to prevent the simultaneous descent of both of said parts and means for 60 operating the said lever, the descent of either of said parts removing it from action, but its contact with its cam when in its highest position serving to cause the shifting of the clutch substantially as described. 65

9. In glass-bottle blowing mechanism, a pair of machines having rotary mold-carrying parts and arranged too near each other to be safely and conveniently rotated together, in combination with clutches for driving them and intervening mechanism for preventing both clutches from being engaged simultaneously. 70

In testimony whereof, I have signed my 75 name to this specification in the presence of two subscribing witnesses.

ALBERT EDWARD CLEGG.
